GEORGES ROESCH, OF PARIS, FRANCE.

FLOAT-RESERVOIR FOR CARBURETERS.

1,270,213.

Specification of Letters Patent. Patented June 18, 1918.

Application filed June 29, 1917. Serial No. 177,730.

To all whom it may concern:

Be it known that I, GEORGES ROESCH, a citizen of Switzerland, residing at Paris, France, have invented certain new and useful Improvements in Float-Reservoirs for Carbureters, of which the following is a specification.

The present invention relates to a liquid fuel reservoir for carbureters having means for maintaining fuel at a constant level. Like other known reservoirs of this general type it comprises a compartment which communicates with the carbureter and is supplied with liquid fuel by means of a feeding device regulated by a float for maintaining a constant level of the liquid fuel in the compartment, but it presents the peculiar feature that the compartment is adapted to turn on an axis, by means of a counter-weight and is always kept in an upright position irrespective of the position of this axis when turning, and that said compartment is located within a receptacle to which the liquid fuel is supplied as will be hereinafter more fully described.

Figure 1 is a vertical cross-section of one form of my present invention.

Fig. 2 is a vertical section on the line A—A in Fig. 1.

Fig. 3 is a central vertical section of a second form of the invention.

Fig. 4 is a vertical cross-section of a third form taken on line B—B of Fig. 5, and

Fig. 5 is an axial vertical section of the construction shown in Fig. 4.

The reservoir comprises a cylindrical body *a* (Figs. 1 and 2) and a cover *b* screwed thereon so as to close it tightly. It is mounted on a flying apparatus (not shown) so that its axis stands at right angles to the longitudinal axis of the apparatus and is provided on its circumference with a pipe neck *a*¹ to which a pipe *c* for the supply of liquid fuel is connected by means of a nipple *d*.

A cylindrical compartment *e* is inclosed within the body *a* and turns on the same axis. This is composed of a body *e*¹ and a cover *e*² screwed thereunto. It is likewise fitted laterally with two axial pipe-necks *e*³, *e*⁴, journaled by means of ball-bearings *f*, *g* in the side walls of the body *a* and of the cover *b*. The liquid fuel is admitted to the reservoir *a*—*b* by means of a valve *i* with a seat *i*¹ and a valve *i*² moving in a guide *i*³. The valve by its own weight tends to leave

the seat but is pressed against it by an arm *j*¹ connected to a float *j*. Arm *j*¹ is fulcrumed at *j*² inside of the compartment *e*. Through the combined action of the valve 60 and float the level of the liquid within the compartment *e* is kept constant. The fuel leaves this compartment through the neck *e*⁵ which extends nearly to the bottom of the compartment by a radial pipe *e*⁶ and terminates on the outside of the compartment in a conically shaped end pressed by a helical spring *k* against a corresponding circular seat of a neck *a*² on the body *a*, the helical spring acting through the body *e*¹ 70 and its cover *e*². This neck *a*² is connected to the inlet of a carbureter of any type. The neck *e*⁴ likewise is continued inside of the compartment *e* by a radial pipe *e*⁶ running in an opposite direction from the pipe 75 *e*⁵ and reaching nearly to the top of the inside of compartment *e* for securing the communication between *e* and the atmosphere. This neck *e*⁴ passes through a stuffing box *l* provided with a lateral neck *b*¹ of the 80 cover *b*.

A counter-weight *m* inside of the compartment always keeps this compartment in an upright position irrespective of the inclination of the reservoir *a*—*b*. A clamping collar *n* provided with an indicator *o* for indicating at any moment on a scale the relative position of the compartment is fitted on the neck *e*⁴.

The working of this form of the invention 90 is as follows:

The liquid fuel passes through neck *a*¹ into the reservoir *a*—*b* and nearly fills the space between it and compartment *e*. The fuel is admitted as fast as is needed by the 95 valve *i* regulated by the float *j*, and will therefore be kept practically at the same constant level within the compartment *e* and from there it will flow to the carbureter through pipe *e*⁵ and through necks *e*³, *a*²; 100 the escape or the inlet of air as the case may be taking place through the neck *e*⁴.

If the flying apparatus is ascending or descending the reservoir *a*—*b* will be inclined with the apparatus, but the compartment 105 or receptacle *e* turning on its axis, will be maintained in its upright position by the counter-weight *m*.

Whatever may be the position of this axis liquid fuel in the compartment *e* will always be kept at the same level determined by the adjustments of the float *j* and valve *i*. 110

The pilot of the flying apparatus is able to observe at every moment the position of the reservoir by a glance at the indicator e and to regulate the same if necessary.

- 5 The counter-weight m as shown in Figs. 1 and 2 is located inside of the compartment, but as will be understood may also be employed in other equivalent manners without departing from the nature of my invention.
- 10 In the second form of the invention as shown in Fig. 3 the cylindrical compartment e^x is likewise provided with two lateral necks e^3 , e^4 , the first neck e^3 communicating with an elbow conduit q provided within the side wall of the cylindrical body a^x and through which the fuel supply passes to the carburetor, and the second neck e^4 being rigidly connected with a pipe r and adapted to turn with this pipe and with the counter-weight p made in one piece and located outside of the reservoir. The neck e^3 has a conically shaped end adapted to contact with a corresponding annular surface on one side of a ring s located in a chamber 25 provided therefor in the body a^x , and the neck e^4 has a similar conical surface adapted to contact with a corresponding surface at the inner end of a sleeve t fitted within the neck b^1 of the cover b^x . The sleeve t is 30 T-shaped in longitudinal section and is surrounded for a certain distance by a ring t^1 made for instance of cork and pressed by a spring k^x against the inner surface of neck b^1 and kept in place by a washer t^2 fixed to the sleeve. The spring k^x bears against a plug u screwed into neck b^1 and is sufficient for tightening the joint between the surface of sleeve t and the conical surface on neck e^4 , for pushing the whole compartment e^x 35 from the left to the right as viewed in this figure, and for causing neck e^3 to press against the annular seat of the ring s , and for tightening this joint, any leakage between sleeve t and inner surface of b^1 being 40 prevented by the ring t^1 . Consequently the tightness of the neck e^4 does not depend on a stuffing-box, which as experience has shown, is not quite so easily adjusted if the free play of compartment e^x is to be maintained with safety.
- 45 The pipe r is journaled by means of ball-bearings v in a support w fixed to a bracket b^3 made in one piece with the cover b^x .
- In the structure shown in Figs. 4 and 5 50 the reservoir a^x has a cylindro-conical shape and by means of screws x is screwed on the wall y^1 of a casing y inclosing the spraying-nozzle z of the carburetor fed from the reservoir. The compartment e^x is made in a lower part e^1 and an upper cover e^2 and is provided with two necks e^3 , e^4 journaled within the ball-bearings f^x , g^x seated within wall y^1 and within the body a^x .

The neck e^4 connected rigidly with a pipe 55 e^5 extends into the inside of the cover e^2 and

makes communication with the outside atmosphere through a hole in a washer 2 and a hole in a plug a^2 .

The necks e^3 , e^4 are provided respectively with annular rims e^7 , e^8 in contact with washers 1 , 2 made for instance of fiber, the washer 1 being located in a chamber within wall y^1 and the washer 2 in a chamber in the body a , where it is kept in place by the screw-plug a^2 . A spring k^x presses against a smaller washer 3 in contact with the washer 2 inside of plug a^2 , and maintains the washer 2 against the conical rim e^8 of the neck e^4 . The pressure of this spring k^x also acts through compartment e^x from the right to the left so as to press rim e^7 against washer 1 and thus secure a tight joint on the left side as well as on the right side of compartment e^x .

As shown in Figs. 4 and 5 the pipe neck e^1 for the liquid fuel inlet may be at the bottom instead of at the side of the casing and as will be understood, various other and equivalent constructions may be adapted and used without departing from the nature and spirit of my invention.

I claim as my invention:

1. A fuel reservoir for carburetors comprising a casing, a receptacle pivotally mounted in the casing and counter-weighted to be maintained in an upright position therein, a fuel inlet connection to the casing, means for admitting fuel from the casing to the receptacle and maintaining a constant fuel level therein, and a fuel outlet connection from the said receptacle.

2. A fuel reservoir for carburetors comprising a casing, a receptacle pivotally mounted in the casing and counter-weighted to be maintained in an upright position therein, a fuel inlet connection to the casing, means for admitting fuel from the casing to the receptacle and maintaining a constant fuel level therein, a fuel outlet connection from the said receptacle, and means for making communication between the interior of the receptacle and the atmosphere.

3. A fuel reservoir for carburetors comprising a casing, a receptacle within the casing, a fuel inlet connection to the casing, means for admitting fuel to the receptacle and maintaining the same at a constant level therein, an outlet pipe connection by which the receptacle is pivotally mounted at one side thereof in the said casing, a pipe connection making communication between the interior of the receptacle and the atmosphere and by which the said receptacle at the other side thereof is pivotally mounted in the said casing, and means for counter-weighting the said receptacle so as to maintain the same in an upright position.

4. A fuel reservoir for carburetors comprising a casing, a fuel receptacle within the casing, a fuel inlet connection in the casing,

a valve operating in the walls of the receptacle for admitting fuel thereto from the casing, means within the receptacle for controlling said valve to maintain the liquid 5 therein at a constant level, a pipe connection at one side of the receptacle and by which the same is pivotally mounted in the casing, the said pipe connection being a fuel outlet, a pipe connection at the opposite side of the 10 receptacle and by which the receptacle is also pivotally mounted in the casing, the last aforesaid pipe connection making communication between the interior of the receptacle and the atmosphere, and means by which the 15 receptacle is counter-weighted to maintain the same in an upright position.

5. A fuel reservoir for carbureters comprising a casing, a fuel receptacle within the same, a fuel inlet connection in the casing, 20 a valve operating in the walls of the receptacle for controlling the admission of fuel thereto from the casing, a lever pivotally mounted within the receptacle, a float carried by said lever and adapted through the

same to control the said valve to maintain 25 a constant level of the fuel within the receptacle, a pipe connection at one side of the receptacle extending approximately to the bottom thereof and by which the receptacle at this side is pivotally mounted in the 30 casing, the said pipe connection being a fuel outlet, a pipe connection at the opposite side of the receptacle extending approximately to the top thereof and by which the said receptacle is pivotally connected at its opposite 35 side in the said casing, the last aforesaid pipe connection making communication between the interior of the receptacle and the atmosphere, and a counter-weight by means of which the receptacle is maintained in an 40 upright position within the casing.

In testimony whereof I have affixed my signature in presence of two witnesses.

GEORGES ROESCH.
